TOOL LIFT FOR AN AGRICULTURAL
IMPLEMENT

Fred N. Sharp, Flint, Mich., assignor, by decree
of distribution and by mesne assignments, to
Lucille S. Killeen, Flint, Mich.

Application April 16, 1947, Serial No. 741,874

8 Claims. (Cl. 97—189)

1

This invention relates generally to a wheeled tool lift for a power driven, "walk behind" agricultural implement and particularly to an improved type thereof which automatically provides for controlled engagement and disengagement of ground working tools with the ground.

There are known to exist a variety of tool lifts especially adapted to use with the conventional, small, garden type, tractor-cultivator. However, those tool lifts presently in known use require direct manual operation during at least some part of their operating cycle of raising and lowering the cultivating tool. Persons familiar with the handling of said conventional, small, garden type, tractor-cultivators are acquainted with the fact that an operator usually has both hands fully occupied in steering and controlling the said tractor-cultivator at about that time when the position of the tool lift needs changing. This situation occurs particularly as the cultivator is to be turned around at the end of a row.

Consequently, there is a recognized need for a completely automatic, tool lift adapted to use with said small tractor-cultivators of the "walk behind" type.

Accordingly, a major object of this invention is to provide an improved, wheeled tool lift for said conventional, small, garden type tractor-cultivator, which tool lift operates completely automatically with respect to said tractor-cultivator.

A further object of this invention is to provide a tool lift as aforesaid which automatically sets and resets itself in positions with respect to the chassis of said tractor-cultivator whereby the said cultivating tool will be positively and automatically held in a plurality of adjustably predetermined positions with respect to the surface of the ground.

A further object of this invention is to provide a tool lift as aforesaid which requires no direct manual operation.

A further object of this invention is to provide a tool lift as aforesaid which is simple and economical to produce.

A further object of this invention is to provide a tool lift as aforesaid which can be readily and adjustably mounted upon a said conventional tractor-cultivator by an unskilled workman.

Other objects and purposes of this invention will become apparent to persons familiar with this type of equipment upon referring to the accompanying drawings and upon reading the following specifications.

2

In order to meet those objects and purposes heretofore mentioned, as well as others incidental thereto and associated therewith, I have conceived an improved wheeled tool lift having a bracket for suitable, adjustable attachment of the tool lift to the chassis of the said tractor-cultivator and slidable support of a wheel standard, to which the wheel of said wheeled tool lift is secured at its lower extremity. Said bracket and said wheel standard are provided with means including a cammed pawl, whereby said wheel may be automatically held at certain positions with respect to said tractor-cultivator chassis, as desired and/or as required.

For a preferred embodiment of the invention, herein described, attention is directed to the drawings in which:

Figure 1 is a side elevation view of a conventional, garden type tractor-cultivator equipped with the automatic tool lift to which this invention relates.

Figure 2 is a side elevation view of the said automatic, wheeled tool lift, and includes a fragment of the tractor-cultivator chassis at the point where said tool lift engages said chassis.

Figure 3 is an end view of said automatic, wheeled tool lift including said fragment of the said tractor-cultivator chassis.

Figure 4 is a side view of said tool lift with the wheel standard in the extended position.

Figure 5 is a fragmentary side view of a tool lift showing an alternate bracket and cammed pawl.

Figure 6 is a fragmentary side view of the alternate tool lift, shown in Figure 5, showing the wheel standard in extended position.

Figure 7 is a cross-sectional view of Figure 2 taken along the line VII—VII.

40 A conventional, small, garden type, "walk behind" tractor-cultivator, including a preferred embodiment of the tool lift comprising the invention, is shown in Figure 1, for purposes of illustration only, as having a chassis or frame 10 which may be fabricated from any type of suitable material, such as channels welded together. Said chassis 10 may be supported by a pair of any convenient, conventional tractor wheels 11 and may in turn support upon one end thereof a

50 suitable driving means such as, for example, an internal combustion engine 12 for the purpose of driving one or both of said wheels 11 by any appropriate means not shown. That end of said chassis, remote from the end supporting said engine, will advantageously support an appropri-

ate cultivating tool 13 in any convenient manner.

The automatic tool lift 15 is preferably but not necessarily supported, adjustably, upon one of the longitudinal members 50 of said chassis 10 between or behind said wheels 11 and said cultivating tool 13 by means described herein-after. A pair of handle bars 14 is suitably secured to said chassis 10 in the vicinity of that point where said chassis is supported upon said wheels 11, which point is advantageously approximately the center of gravity of the entire device.

It will be understood that, insofar as this particular embodiment of the invention is concerned, the exact structure and type of said tractor-cultivator, with which the said wheeled tool lift is used, is not limited, provided only that it has suitable means whereto the tool lift bracket 16 of said tool lift 15 may be secured, such as the channel iron chassis 10.

As shown more clearly in Figures 2, 3 and 4, the said tool lift bracket 16 is comprised of a pair of central plates 20 and 21, each of which has a slide support member 22 and 23 respectively extending upwardly therefrom and integral therewith or welded, or otherwise fastened thereto as convenient. These slide support members are substantially longer than wide and as here shown are integral at their lower ends with their respective central plates. Said central plates and their respectively connected slide support members may be fabricated from any suitable material, such as sheet metal, provided that such material is of sufficient strength to withstand the stresses to which said tool lift bracket will be exposed.

The said central plate 21 may be rectangular and flat as appearing in Figures 3 and 4, whereas said central plate 20, whose peripheral contour is also rectangular and advantageously coincident with that of the central plate 21, is bent so as to provide a vertical guide groove 24 for the guidance and support of the wheel standard 30. Said slide support member 22, which projects vertically from said central plate 20 in line with said vertical guide groove 24, contains a longitudinally disposed centrally located guide slot 25 which extends approximately from the junction point between said central plate and said slide support member to a point spaced from the free extremity 26 of said slide support member.

The longitudinal or vertical edges 27 of said slide support member 22 may be advantageously flanged outwardly thereby imparting additional strength to said slide support member 22, as shown in Figure 7.

As shown in Figure 4, the slide support member 23 extends vertically from, and is preferably an integral part of, the central plate 21 in substantially the same manner as said slide support member 22 is associated with said central plate 20. The slide support members being advantageously mirror images of each other, the support member 23 contains a guide slot 28 which is substantially opposite to, and aligned with, said slot 25 of said support member 22 when the said central plate 21, is approximately superimposed as illustrated in Figures 2 and 4, upon said support plate 20. The longitudinal or vertical edges 29 of said support member 23 may also be flanged outwardly for additional strength thereof, as shown in Figure 7.

The central plate 21 is preferably secured to the other central plate 20 by any suitable means,

such as riveting, welding or brazing, so that said slide support members 22 and 23 will be parallel and opposite each other, and the said flanges 27 and 29, respectively, will extend away from each other, as shown in Figure 7. A passageway 31 will be defined by said vertical guide groove 24 and said central plate 21 for slidable reception of the said reciprocable wheel standard 30, which may be fabricated from any type of suitable material, such as bar stock. Said wheel standard may be attached at its lower end to the stem 32 of a conventional wheel fork 33 by any suitable means, such as welding.

Near the upper end of said wheel standard there is provided a bolt opening 34, which is aligned with said slots 25 and 28 when said bracket 16 is operably engaged by said wheel standard 30. A suitable bolt 35, which slidably extends through both of the said slots 25 and 28 and the bolt opening 34, not only restricts the vertical, reciprocable motion of said wheel standard 30 within said bracket 16 to the extent of said slots, but also provides lateral guidance therefor.

A stop notch 36 is provided in an edge of said wheel standard 30 for engagement by the pointed lower extremity 37 of the cammed pawl 38 which is rotatably supported at its upper extremity upon a pivot bolt 39. Said stop notch is advantageously near to the upper extremity of said wheel standard, however, it may be at any point between said extremities of said wheel standard as required or desired. The cammed pawl 38 has along one edge a cam surface 40 whose detailed shape and purpose will be described hereinafter.

Said cammed pawl 38 may be of any suitable material, but is preferably fabricated from steel plate of sufficiently less thickness than the normal distance between said slide support members 22 and 23 to effect easy passage of said pawl therebetween. Said pivot bolt 39 is received through suitable openings in the slide support members 22 and 23 near their upper ends so that the said pawl is free to rotate therebetween about said pivot bolt, and is placed sufficiently to one side of the wheel standard 30 that its cam surface 40 is away from the slide support members, as illustrated in Figures 2 and 4, but its lower end 37 will extend across at least part of the upper end of said wheel standard when said wheel standard is lowered sufficiently to permit said pawl to hang freely.

Said wheel fork 33 rotatably supports a wheel 41, which may be of any convenient conventional type, upon the shaft 48. The bracket 16 may be removably and adjustably attached to the chassis 10 in any convenient way, for example, by means of a pair of U-bolts 49 which loop around a longitudinal member 50 of said chassis and extend through suitable openings in the plates 20 and 21, as illustrated in Figure 3.

Figures 5 and 6 illustrate an alternate bracket 53 and alternate cammed pawl 54 suited to heavier duty than the bracket 16 and cammed pawl 38. Said cammed pawl 54 is provided with a hook 55 adjacent to its upper end and such end is rotatably supported upon said slide support members 56 and 57 (corresponding to slide support members 22 and 23 in the Figures 1 to 4 inclusive) by means of the pivot bolt 58. Said hook 55 may engage the wheel standard 59 either within the stop notch 60 or at the end 61 thereof, as shown in Figures 5 and 6, respectively.

The central plates 62 and 63 of said alternate bracket 53 may be substantially the same as the

central plates 20 and 21 of the bracket 16 except that the vertical groove 64 in the plate 62 is wider than the wheel standard 59 and therefore necessitates a guide block shim 65, which may be held in position by any suitable means such as the rivets 69. The reciprocable motion of the wheel standard 59 is guided and limited by means of the slideable association between the guide slots 66 and 67 in the slide support members 56 and 57, respectively, and the bolt 68 which is received through a suitable opening in said wheel standard 59 adjacent to the end 61 thereof.

In operation, the tool lift 15 is first secured to a longitudinal member of said chassis, as aforesaid, by means of the U-bolts 49 and appropriate lateral adjustment of said bracket 16 is made with respect to said chassis. Said stop block 45 shown in Figure 4 may be adjustably positioned on the wheel standard 30 as required if it is desired to limit the depth to which the said tool 13 extends into the ground when the said tractor-cultivator is being operated. The said wheel standard is free to move reciprocably as aforesaid, vertically with respect to the chassis 10 of the said tractor-cultivator, within the limits imposed by the stop block 45 at the one end and the upper ends of guide slots 25 and 28 at the other end.

If it is desired to suspend the cultivating tool 13 in a position of non-engagement with the ground, the handle bars 14 are raised, thereby lifting the chassis 10 and tool lift bracket 16 attached thereto until the relative downward motion of the wheel standard 30 effects an entry into the stop notch 36 by the free extremity 37 of the cammed pawl 38. If the said handle bars 14 are then released, the said cam extremity 37 will slide into secure, positive engagement with said stop notch 36. In such position, said tool 13 will be held above the ground, indicated in phantom at 17 in Figure 1.

It will be noted that the pawl 38 is so constructed and suspended that its extremity 37 will bear against that edge of said wheel standard 30 containing the stop notch 36. The said engagement of said notch 36 by said extremity 37 thereby becomes automatic when a downward motion of said wheel standard relative to the slide support members is effected.

If it then becomes desirable to return said tool 13 to a position of engagement with the ground, said handle bars 14 are again raised, thereby lifting said chassis 10 and said tool lift bracket 16, until the said wheel standard 30 drops below the point of engagement thereof with the lower end 37 of said pawl 38. Said pawl then swings across the inclined top 41 of said wheel standard 30 into a position of equilibrium, approximately as shown in Figure 4. If the handle bars are then lowered, the chassis 10, hence the bracket 16, moves downwardly thereby effecting a relative upward movement of the wheel standard until the said inclined top 41 engages the cam surface 40 of said pawl 38.

The inclination of said top 41 is designed to cooperate with said cam surface 40 in producing a rotation of said pawl 38, shown as counter-clockwise about its supporting bolt 39 in Figure 4, as said wheel standard moves relatively upwardly. Such rotation continues until the pawl is pushed over the top of its point of pivotal support whereupon it further continues by gravity until it again contacts the said wheel standard, as shown in Figure 2, whereupon it is ready to repeat the cycle. The wheel standard is then

free to move upwardly until said bolt 35, attached to said upper extremity thereof, engages the upper ends of said guide slots 25 and 28, or until the stop block 45 engages the bottom of said bracket 16 if such stop block is used. This completes an operating cycle of said tool lift, by means of which and during which the said tool 13 was first suspended inoperatively and was then returned as desired to a position permitting engagement with the ground, none of which required disengagement of the operator's hands from the cultivator handles.

The operation of a tool lift, illustrated in Figures 5 and 6, is identical in substance to the operation of the tool lift described above and appearing in Figures 1 through 4. However, the hook 55 on said pawl 54 provides for the positive engagement of said pawl with the wheel standard 59 at two different positions instead of one. Such positions comprises the stop notch 60, as shown in Figure 5, and the top 61 of said wheel standard 59, as shown in Figure 6.

The manner in which said top 61 of said wheel standard 59 engages said pawl 54 and urges it to rotate or recock itself automatically is substantially the same as described hereinbefore with respect to the wheel standard 30 and the pawl 38.

It will be observed, especially where the smaller tractor-cultivator is involved, that while said tool 13 is engaging the ground, the tool lift may often support no weight, but will be free to reciprocate within said bracket as the wheel 47 continually adjusts itself to the terrain and the motion of the tractor, and while the cammed pawl remains in a cocked position. For larger machines, where it is desired that the wheel 47 support the weight of the rear end of the machine during the cultivating operations as well as in turning operations, the stop block 45 on the wheel standard 30 and the modified bracket 53 and pawl 54 offer alternative means, by which said tool lift can be altered, within the scope of the invention, to effect such purposes.

Although the above mentioned drawings and description apply to a particular, preferred embodiment of the invention, it is not my intention, implied or otherwise, to eliminate other variations or modifications which do not depart from the scope of the invention unless specifically stated to the contrary in the hereinafter appended claims.

I claim:

1. An agricultural implement having a frame movable toward and away from the ground and including means mounting a tool thereon for movement with said frame between operative and inoperative position, and having also means carried by said frame for supporting such tool in either operative or inoperative position with reference to the ground, said means comprising: a wheel supported by wheel-supporting means slidably mounted on said frame; pawl means supported upon said frame and cooperating with said wheel-supporting means for holding said tool in inoperative position with respect to the ground, said pawl having a cam surface and being pivotally suspended so that said cam surface will, when said pawl is unobstructed, be engageable by an upper end portion of said wheel supporting means movable toward and away therefrom for substantially complete rotation of said pawl about its pivot point as the tool is moved from inoperative to operative position.
2. An agricultural implement having a frame

portion movable toward and away from the ground and including means mounting a tool thereon for movement with said frame from operative to inoperative position, and having also means carried by said frame for supporting such tool in either operative or inoperative position with reference to the ground, said means comprising: a wheel supported by means including a vertically reciprocable bar having a notch therein; pawl means connected to the tool supporting means and enterable into said notch in one position of the tool with respect to the ground, said pawl being supported for pivotal movement in a plane parallel to the line of reciprocation of said bar, having a cammed surface on its one edge, and so supported that when said bar is in its lowermost reciprocable position the cam surface remote from the pivoted end of said pawl will at least in part substantially oppose the upper end of said bar, the curvature of said cam surface being such that, as said bar is moved upward relative to said pawl, it will rotate said pawl over the top of its point of pivotal support, whereby it will return by gravity therefrom into a position against said bar free from engagement with said notch, and means limiting the upward movement of said bar relative to said cam.

3. An agricultural implement having a frame portion movable toward and away from the ground and including means mounting a tool thereon for movement with said frame from operative to inoperative position, and having also means carried by said frame for supporting such tool in either operative or inoperative position with reference to the ground, said means comprising: a wheel supported by means including a vertically reciprocable bar having a notch therein; pawl means connected to the tool supporting means and enterable into said notch in one position of the tool with respect to the ground, said pawl being supported for pivotal movement in a plane parallel to the line of reciprocation of said bar, having a cammed surface on its one edge, and so supported that when said bar is in its lowermost reciprocable position the cam surface remote from the pivoted end of said pawl will at least in part substantially oppose the upper end of said bar, the curvature of said cam surface being such that, as said bar is moved upward relative to said pawl, it will rotate said pawl over the top of its point of pivotal support, whereby it will return by gravity therefrom into a position against said bar free from engagement with said notch means located on said bar, and cooperating with means affixed to said frame for limiting the upward movement of said bar relative to said cam.

4. An agricultural implement having a frame portion movable toward and away from the ground and including means mounting a tool thereon for movement with said frame from operative to inoperative position, and having also means carried by said frame for supporting such tool in either operative or inoperative position with reference to the ground, said means comprising: a wheel supported by means including a vertically reciprocable bar having a notch therein; pawl means connected to the tool supporting means and enterable into said notch in one position of the tool with respect to the ground, said pawl being supported for pivotal movement in a plane parallel to the line of reciprocation of said bar, having a cammed surface on its one edge, and so supported that when said bar is in its lowermost reciprocable position the cam

surface remote from the pivoted end of said pawl will at least in part substantially oppose the upper end of said bar, the curvature of said cam surface being such that as said bar is moved upward relative to said pawl it will rotate said pawl over the top of its point of pivotal support, the upper end of said bar being contoured to cooperate with the cam surface of said pawl, whereby it will return by gravity therefrom into a position against said bar free from engagement with said notch; and means limiting the upward movement of said bar relative to said cam.

5. An agricultural implement having a frame portion movable toward and away from the ground and including means mounting a tool thereon for movement with said frame from operative to inoperative position, and having also means carried by said frame for supporting such tool in either operative or inoperative position with reference to the ground, said means comprising: a pair of central plates adjustably affixed to said frame and defining a guideway therebetween, and vertically slotted, spaced guide means extending above said plates at least partially defining a continuation of said guideway; a wheel supported upon a vertically reciprocable bar received within said guideway and means associated with said bar extending through the slotted portions of said guide means; pawl receiving means associated with said bar; a pawl pivotally supported between said spaced guide means and suspended so that its lower end is urged by said gravity against said bar and into operative cooperation with said pawl receiving means in one reciprocable position of said bar with respect to said pawl, said pawl having a cam surface movable by gravity in another reciprocable position of said bar into cooperation with a portion of said bar, the curvature of said cam surface being such that as said bar is moved upward relative to said pawl it will rotate said pawl over the top of its point of pivotal support, whereby it will return by gravity therefrom into a position against said bar free from engagement with said notch limiting the upward movement of said bar relative to said cam.

6. An agricultural implement having a frame portion movable toward and away from the ground and including means mounting a tool thereon for movement with said frame from operative to inoperative position, and having also means carried by said frame for supporting such tool in either operative or inoperative position with reference to the ground, said means comprising: a pair of central plates adjustably affixed to said frame and defining a guideway therebetween, and vertically slotted, spaced guide means extending above said plates at least partially defining a continuation of said guideway; a wheel supported upon a vertically reciprocable bar received within said guideway and means associated with said bar extending through the slotted portions of said guide means; pawl receiving means associated with said bar; a pawl pivotally supported between said spaced guide means having its center line constituting an arc and suspended so that its lower end is urged by gravity against said bar and into operative cooperation with said pawl receiving means in one reciprocable position of said bar with respect to said pawl, said pawl having a cam surface of progressively increasing radius from the pivoted end to at least near the free end thereof movable by gravity in another reciprocable position of said bar into cooperation with a portion of

said bar, the curvature of said cam surface being such that as said bar is moved upward relative to said pawl it will rotate said pawl over the top of its point of pivotal support, whereby it will return by gravity therefrom into a position against said bar free from engagement with said notch and means located on said bar and co-operating with means affixed to said frame for limiting the upward movement of said bar relative to said cam.

7. In an agricultural implement having a frame movable toward and away from the ground, said frame having means supporting a tool thereon for movement therewith, the improvement comprising: wheel support means slidably mounted on said frame and a wheel rotatably supported upon said support means; a pawl, and means pivotally supporting said pawl on said frame, said pawl being cooperable with said support means for holding said tool in a raised position, and said pawl having a cammed edge engageable by the upper end of said support means for rotating said pawl about its pivot point and thereby releasing said tool from said raised position.

8. In an agricultural implement having a frame vertically movable toward and away from the ground, said frame having means supporting a tool thereon for movement of said tool therewith between operative and inoperative positions of said tool, the improvement comprising: a bar ver-

tically reciprocably supported upon said frame, said bar having a notch therein near the upper end thereof; means limiting the upward and downward reciprocal movement of said bar with respect to said frame; a wheel rotatably supported upon the lower end of said bar; a pawl and means pivotally supporting said pawl near one end thereof upon said frame adjacent to the upper end of said bar and substantially within a plane parallel therewith, said pawl being cooperable with said notch for holding said tool in the inoperative position, and said pawl having a cammed edge engageable by the upper end of said bar as said frame is first raised and then lowered with respect to said bar, said cammed edge being so curved that said pawl is completely rotated around its pivot point by the upper end of said bar in cooperation with gravity as said frame is lowered, thereby permitting lowering said tool into operative position.
